ABSTRACT

A combination or permutation padlock has a case which supports a movable shackle and contains a pair of locking bolts movable into locking engagement with the legs of the shackle to retain it in a locked position. A control assembly received in the case includes a frame which supports a movable blocking member and a permutation mechanism for controlling movement of the blocking member to and from a blocking position wherein the blocking member prevents retraction of the locking bolts from engagement with the shackle legs. The frame top wall cooperates with the upper wall of the case to confine the locking bolts for movement into and out of locking engagement with the shackle legs. A filler block supported by the frame provides structural support for the frame top wall and receives a drive pin which extends through a wall of the case and a wall of the frame to retain various parts of the lock in assembled relation. Integral annular flanges on combination wheels which comprise the permutation mechanism cooperate with slots in the bottom wall of the frame to prevent insertion of a picking tool into the case.

FIG. 6

FIG. 7

PADLOCK CONSTRUCTION

BACKGROUND OF THE INVENTION

This invention relates in general to improvements in padlocks of combination or permutation type and deals more particularly with improvements in padlocks of the type shown and described in U.S. Pat. Nos. 2,853,868 and 3,419,893, assigned to the assignee of the present invention.

In the permutation padlocks disclosed in the aforesaid patents, one wall of a frame, which comprises part of a control assembly, cooperates with an associated wall of a lock case in which the assembly is received to confine a pair of locking bolts for movement into and out of locking engagement with legs of a shackle. It has been found that if a sufficiently strong pull is applied to the shackle of such a padlock, the locking bolts may exert sufficient bending force upon the confining wall of the frame to deform it and, thereby, impair the function of the lock. The present invention is primarily concerned with improvements in construction of such a lock without sacrifice of advantages derived from use of a control assembly frame for the aforesaid purpose. The invention is further concerned with provision of improved control mechanism in a lock of the aforescribed general type to discourage picking by unauthorized persons not having knowledge of the prevailing combination.

SUMMARY OF THE INVENTION

In accordance with the present invention, a padlock of the aforescribed general type is provided in which a filler block cooperates with walls of a control assembly frame to provide structural reinforcement therefor and with a drive pin for improved assembly retention of the various parts which comprise the locking structure. Integral flanges on the combination wheels which comprise the control mechanism cooperate with slots in an associated wall of the frame to defeat entry of a picking tool or the like into the case of the lock.

BRIEF DESCRIPTION OF THE DRAWINGS

FIG. 1 is a perspective view of a permutation padlock embodying the present invention.

FIG. 2 is a somewhat enlarged fragmentary side elevational view of the padlock of FIG. 1, and shows the case, portions of the control mechanism and the locking bolts in vertical central section.

FIG. 3 is a sectional view taken generally along the line 3-3 of FIG. 2.

FIG. 4 is a sectional view taken along the line 4-4 of FIG. 2.

FIG. 5 is a fragmentary sectional view taken along the line 5-5 of FIG. 2.

FIG. 6 is an exploded perspective view of the control assembly of the padlock of FIG. 1, however, for clarity of illustration, the locking member thereof is not shown.

FIG. 7 is a somewhat enlarged fragmentary sectional view showing a permutation wheel oriented as shown in FIG. 2.

DETAILED DESCRIPTION OF DETAILED EMBODIMENT

The novel construction of the present invention is particularly adapted for use with padlocks of either

combination or permutation type. Turning now to the drawings and referring first particularly to FIGS. 1-3 thereof, a permutation padlock embodying the present invention, and indicated generally by the reference numeral 10, comprises a hollow case 12 which supports a securing element or shackle 14 for movement between locked and unlocked or open positions. The shackle 14 is biased toward open position by a spring 16 and is retained in locked position, as shown, by a pair of oppositely disposed locking bolts 18, 18 which cooperate in locking engagement with the legs of the shackle 14 to retain it in its locked position. The locking bolts are biased transversely outwardly in opposite directions toward projected positions in locking engagement with the shackle by a spring 20 positioned between the locking bolts and retained on a pin. A control assembly received in the case 12 and indicated generally by the reference numeral 22 includes a frame 24. The latter frame supports a movable blocking member 26 which blocks the locking bolts in projected position and a permutation mechanism, indicated generally at 28, which controls movement of blocking member to and from its blocking position. Since the novel features of the present invention reside in the construction and arrangement of the parts thereof, the illustrated locking mechanism will be hereinafter only generally described. However, reference may be had to the aforesaid U.S. patents for a more complete disclosure of the illustrated permutation mechanism.

In accordance with the present invention, the control assembly 22 cooperates with the case 12 to confine the locking bolts 18, 18 for movement between projected and retracted positions and includes a filler block 30 which cooperates with the frame 24 to provide improved structural confinement for the bolts. The filler block also cooperates with a drive pin 32 to provide improved structural retention of the control assembly 22 in the case 12, as will be hereinafter further discussed.

Considering now the structure of the lock 10 in further detail, and as oriented in the drawing, the case 12 has a continuous peripheral side wall 34 and an upper wall 36 which cooperate to define a cavity 38 opening through the lower end of the case. The locking bolts 18, 18 are received in the cavity 38 adjacent the upper wall 36 for sliding engagement therewith and confined in the case 12 by the control assembly 22 or more specifically, by the frame 24 which comprises part of the latter assembly. The frame 24 is preferably formed from sheet metal and includes a rear wall 40, a top wall 42 spaced downwardly from the upper wall 36 and a pair of transversely spaced side walls 44 and 46 which respectively define upwardly facing bearing surfaces 48 and 50 spaced downwardly from the top wall 42. The frame 24 also includes a bottom wall 54 which forms a closure for the lower end of the case 12 and has a generally arcuate central portion indicated at 56. The arcuate central portion extends transversely of the bottom wall 54 and has a plurality of transversely spaced slots 58, 58 which open therethrough. Each slot 58 is partially defined by a pair of opposing transversely spaced side walls 60, 60, as best shown in FIG. 2.

The shape of the filler block may vary, however, the illustrated filler block 30 has a generally trapezoidal shape and includes a pair of transversely projecting end portions 62, 62 each of the latter end portions has a downwardly facing abutment surface 64 thereon. The

filler block 30 is inserted in the open front end of the frame 24 before the frame is assembled within the case 12. The upper surface of the filler block bears against the lower surface of the top wall 42 and the abutment surfaces 64, 64 rest upon the bearing surfaces 48 and 50, respectively. The control assembly 22 is retained in assembled relationship with the case 12 by a fastener or drive pin 32 which passes through the wall of the case 12, the frame rear wall 40 and which is received in drive fit engagement in an opening in the filler block 30.

The permutation mechanism 28 for controlling movement of the blocking member 26 comprises a transversely spaced series of combination or permutation wheels 66, 66 carried by a shaft 67 journaled on the side walls 44, 46 and extending transversely therebetween, the axis of the latter shaft being indicated at 69. Each wheel 66 has a segment thereof which extends outwardly through an associated one of the slots 58, 58 and a pair of coaxial flanges 68, 68 thereon which extend axially outwardly from opposite sides thereof. Each flange 68 extends transversely outwardly beyond an associated one of the side walls 60, 60 which partially define the associated slot 58. The arcuate central portion 56 of the frame bottom wall 54 has its center of curvature on the axis 69 to closely conform to the contour of the flanges 68, 68, as best shown in FIG. 3. Thus, the flanges 68, 68 and slot walls 60, 60 cooperate to prevent insertion of a picking tool or the like into the case 12.

Each wheel 66 is normally engaged with a lock controlling element in the form of a disc 70 which is rotatably mounted on the shaft 67 and which is cut away at one side thereof to provide a flat (not shown) on the periphery of the disc. Each permutation wheel 66 is retained in set position by means of a spring member 72 which engages a series of notches in the periphery thereof. The blocking member 26 preferably takes the form of a blocking plate which is pivotally supported intermediate its ends on the side walls 44 and 46 and which is adapted to be rocked about its support. The blocking member is retained in position by a spring 74 and by a guide pin 76 which act between the case 12 and the blocking member 26 as best shown in FIG. 3. The blocking member 26 also includes a plurality of transversely, spaced apart fingers 80, 80, shown broken away in FIG. 2, which extend between the permutation wheels and respectively engage the peripheries of the control discs 70, 70. The fingers 80, 80 are biased toward engagement with the discs 70, 70 by the spring 74, as best shown in FIG. 3.

When it is desired to unlock the shackle 14, the controlling discs 70, 70 are rotated by their respective combination wheels 66, 66 until the proper combination appears thereon at the bottom of the case. All of the flats on the control discs will then be aligned with adjacent and cooperating fingers 80, 80 on the blocking member 26 whereupon the spring 74 causes the blocking member 26 to pivot to a position wherein the finger 65 swings outwardly from between the bolts 18, 18. The bolts may then be readily forced inwardly toward their retracted position by a pull on the shackle 14, or if desired, the spring 16 may be made to provide sufficient biasing force on the shackle to move it into open position by camming the bolts inwardly against the pressure of the spring 20. The illustrated lock 10 is also provided with a permutation mechanism to permit

the combination of the lock to be readily changed. The latter mechanism is well known in the art, however, for a more detailed disclosure of the latter mechanism or the operation of the lock, which is only generally discussed herein, reference may be had to the aforementioned U.S. patents.

When the lock 10 is in its locked condition, as it appears in FIG. 2, a pulling force exerted upon the shackle 14, relative to the case 12, tends to cause the bolts 18, 18 to rotate in opposite directions so that the inner ends thereof bear upon the central portion of the frame upper wall 42 and exert bending force thereon. However, the latter force is transmitted to the filler block 30 which, in turn, transmits the force to the bearing surfaces 48 and 50 associated with the frame side walls 44 and 46. Thus, the filler block 30 cooperates with the frame side walls to provide structural support for the frame top wall 42.

I claim:

1. A combination padlock having a hollow case including an upper wall and an opening at the lower end thereof, a shackle supported on said case and movable relative thereto between locked and unlocked positions, a pair of locking bolts supported in said case for sliding engagement with said upper wall thereof in opposite transverse directions between projected and retracted positions for engagement with the legs of said shackle in said projected position to retain said shackle in its locked position, means normally urging said locking bolts outwardly in opposite directions toward said projected position, a control assembly including a frame received in said case and having a top wall spaced downwardly from said upper wall and cooperating therewith to confine said locking bolts in said case for movement between said projected and retracted positions, said frame having a bottom wall providing a closure for said opening, said control assembly further including a blocking member mounted on said frame for controlled movement to and from a blocking position, said blocking member in said blocking position having a part thereof disposed between said bolts to positively retain said bolts in said projected position, and a combination mechanism for controlling the movement of said blocking member, a filler block disposed in said case within said frame and extending transversely thereof below said top wall and in bearing engagement therewith, and a drive pin extending into said case through a wall thereof and into said filler block for retaining said locking bolts, said filler block and said control assembly in assembled relation with said case.
2. A combination padlock as set forth in claim 1 wherein said frame includes a pair of transversely spaced apart side walls extending between said top and bottom walls, each of said side walls having an upwardly facing bearing surface thereon, said filler block having end portions extending transversely outwardly therefrom, each of said end portion having a downwardly facing abutment surface thereon engaging an associated one of said bearing surfaces.

3. A combination lock as set forth in claim 2 wherein said frame includes a rear wall connecting said side walls and said top and bottom walls and said drive pin extends in drive fit engagement through said case wall and said rear wall and into said filler block.

4. A combination lock as set forth in claim 1 wherein said bottom wall has a transversely spaced series of

slots therethrough, each of said slots partially defined by a pair of opposing transversely spaced side walls, and said combination mechanism includes a plurality of transversely spaced series of combination wheels journaled for rotation about an axis extending transversely of said frame, each of said wheels having a segment thereof extending outwardly through an associated one of said slots and a pair of coaxial flanges thereon extending axially outwardly from opposite sides thereof,

each of said flanges extending transversely outwardly beyond an associated one of said side walls defining said associated slot.

5. A combination lock as set forth in claim 4 wherein said bottom wall has a transversely extending arcuate portion which has a center of curvature on said axis, said slots being at least partially defined by said arcuate portion.
